CLAIM

The ornamental design for a charging station for cleaning machine, as shown and described.

DESCRIPTION

1.1 is a front view of a charging station for cleaning machine, showing our new design;

1.2 is a rear view thereof;

1.3 is a left-side view thereof;

1.4 is a right-side view of thereof;

1.5 is a top view thereof; and,

1.6 is a perspective view thereof.

The broken lines in the drawings illustrate portions of the article that form no part of the claimed design.

1 Claim, 6 Drawing Sheets
